United States Patent Office

Des. 215,900
Patented Nov. 4, 1969

215,900

DISPLAY STAND

John M. Combs, Montville, N.J., assignor to Mead-Suydam Company, Wayne, N.J., a corporation of New Jersey

Filed Apr. 12, 1968, Ser. No. 11,444

Term of patent 14 years

Int. Cl. D6—01

U.S. Cl. D80—9

FIG. 1

FIG. 2

FIG. 3

FIG. 4

FIG. 1 is a front perspective view of a display stand embodying my new design,

FIG. 2 is a top plan view thereof;

FIG. 3 is a front elevational view thereof, and

FIG. 4 is a side cross-sectional view, taken on line 4-4 of FIG. 3.

The broken line representation of burial vault samples in FIGS. 1, 3 and 4 is for purposes of illustration only.

I claim:

The ornamental design for display stand, as shown and described.
